VACUUM CLEANER

Joseph A. McAnerney, New York, N. Y., assignor
to Electric Vacuum Cleaner Company, Inc., a
corporation of New York

Application April 28, 1939, Serial No. 270,564

1 Claim. (Cl. 15—16)

The present invention relates to vacuum cleaners of the type having the suction producing and dust collecting means arranged within a portable casing which is connected by means of a flexible hose to a suction tube provided with a suction nozzle movable over the surface being cleaned.

The object of my invention is to provide an improved construction in vacuum cleaners of this type by means of which the suction tube may 10 serve as a handle for moving the casing.

For a consideration of what I believe to be novel and my invention, attention is directed to the following description and the claim appended thereto.

15 In the accompanying drawing, Fig. 1 is a side elevation of a vacuum cleaner embodying my invention, the suction tube being shown fixed to the vacuum cleaner casing and serving as a handle for moving the casing; Fig. 2 is an elevation 20 of the vacuum cleaner illustrating its use; and Fig. 3 is a perspective view of the bracket for securing the suction tube to the casing.

Referring to the drawing, there is shown a vacuum cleaner having a vertical casing 1 containing a filter and motor-driven suction fan (not shown). The casing has an inlet 2 connected by a flexible hose 3 to a rigid suction tube 4 provided at its lower end with a nozzle 5 having surface contacting lips 6 and 7. The casing is 30 supported at the front by casters 8, and at the rear by wheels 9. In the use of the cleaner the casing is positioned in a convenient location and the suction nozzle is moved over the surface to be cleaned, the dirt-laden air being drawn 35 through the flexible hose 3 into the casing where the dirt is filtered from the air. While cleaning in this location the casing remains stationary. To use the cleaner in a different location the casing must be moved. This is done by fixing the 40 suction tube 4 to the rear side of the casing, as shown in Fig. 1, so that the suction tube extends

vertically up along the casing side walls and the upper end thereof projects above the casing and serves as a handle by means of which the casing may be tipped so that it is supported solely upon the rear supporting wheels 9. In this position 5 the casing may be easily moved. The upper end of the suction tube is fastened to one of the balls 10 on the casing by a chain 11 which encircles the suction tube and is fastened to the ball by means of an eye 12 and a hook 13. The lower 10 end of the suction tube is fastened to the casing by means of a bracket 14 fixed to the casing and having upwardly extending lugs 15 which extend upward into the nozzle between the nozzle lips 6 and 7, as shown in Fig. 3. The lugs 15 are on 15 the outer ends of arms 16 which are shaped to provide seats for the front nozzle lip 7. With this construction the suction tube may be quickly attached to the casing to serve as a handle. The flexible hose 3 need not be disconnected. By unfastening the suction tube 4 the cleaner is therefore returned to the condition shown in Fig. 2 in which it is ready for use.

What I claim as new and desire to secure by Letters Patent of the United States, is:

In a vacuum cleaner, a vertical casing having suction producing and dirt separating means, rear supporting wheels therefor, a rigid suction tube provided with a suction nozzle at one end and connectible at the other end with one end 30 of a flexible suction hose, an inlet to the casing for connection with the other end of said flexible hose, and means including a bracket fixed to the lower end of the casing and having lugs receiving and holding the suction nozzle for detachably 35 securing the suction tube to the casing in a position extending up along the casing side walls with its upper end serving as a handle by means of which the casing may be tilted rearwardly and moved about on its rear supporting wheels. 40

JOSEPH A. MCANERNEY.
